(57) **CLAIM**

The ornamental design for a portion of a display screen with an animated computer generated icon, as shown and described.

DESCRIPTION

FIG. 1 is a front view of a first image of a portion of a display screen with an animated computer generated icon showing our new design;

FIG. 2 is a front view of a second image thereof; and,
FIG. 3 is a front view of a third image thereof.

The appearance of the image transitions between the images shown in FIGS. 1-3. The process or period in which an image transitions to another forms no part of the claimed design. The broken lines of equal length showing portions of the icon and symbols show environmental structure and form no part of the claimed design. The broken lines of unequal length showing a display screen or portion thereof form no part of the claimed design.
